COMBINATION LADLE AND STRAINER

John K. Mohr, Simi, Calif.

Application December 14, 1948, Serial No. 150,135

Term of patent 14 years

(Cl. D44—29)

To all whom it may concern:

Be it known that I, John K. Mohr, a citizen of the United States of America, and a resident of Simi, in the county of Ventura and State of California, have invented a new, original, and ornamental Design for a Combination Ladle and Strainer, of which the following is a specification, reference being had to the accompanying drawing, forming part thereof.

In the drawing:

Fig. 1 is a side-elevational view of a combination ladle and strainer showing my new design.

Fig. 2 is a top plan view thereof.

Fig. 3 is a perspective view.

I claim:

The ornamental design for a combination ladle and strainer, as shown.

JOHN K. MOHR.
